PEDESTAL TABLE

Harry Laylon, Syracuse, N.Y., assignor to
Dart Industries Inc., Los Angeles, Calif.

Filed Mar. 2, 1973, Ser. No. 337,707

Term of patent 14 years

Int. Cl. D6—03

U.S. Cl. D6—27

FIG. 1 is a perspective front view of a pedestal table embodying my new design;
FIG. 2 is a view in side elevation thereof; and
FIG. 3 is a top view thereof.
I claim:
The ornamental design for a pedestal table, substantially as shown.
